UNITED STATES PATENT OFFICE.

CASIN W. OBERT, OF NEW YORK, N. Y.

LOCKING MEANS FOR INTERNAL-COMBUSTION MOTORS.

1,105,296.

Specification of Letters Patent.

Patented July 28, 1914.

Application filed March 5, 1914. Serial No. 822,635.

To all whom it may concern:

Be it known that I, CASIN W. OBERT, a citizen of the United States of America, and resident of the borough of Brooklyn, in the city of New York, county of Kings, and State of New York, have invented certain new and useful Improvements in Locking Means for Internal-Combustion Motors, of which the following is a specification.

10 This invention relates to locking means for internal combustion motors so as to render such motors inoperative, and thereby prevent the unauthorized use thereof.

The object of this invention is to provide 15 such a combination of parts that the locking into inoperative position may be carried out without danger of injury to any of the operative parts, and at the same time provide such means that the locking is entirely 20 secure and reliable.

For this purpose the invention consists of 25 certain novel features and combinations of parts which will be more fully described and finally pointed out in the claims.

25 In the accompanying drawings, Figure 1 is a side-view of an internal-combustion engine showing my invention applied thereto, in connection with an ignition device known in practice as a magneto, Fig. 2 is an enlarged 30 view of my invention in detail, Fig. 3 is another embodiment of my invention applied to the shaft driving a timer of an internal-combustion engine, Fig. 4 is another embodiment of my invention applied to the member 35 driving the ignition operating shaft in the gear-case of an internal combustion motor, Fig. 5 is another embodiment of my invention applied directly to the timer for such an internal combustion motor, and Fig. 6 40 shows another embodiment of my invention applied directly to the magneto and operating in a slightly different manner, but accomplishing the same result as the other embodiments shown in the various figures.

45 Similar reference characters indicate corresponding parts throughout the different figures of the drawings.

Referring to the drawings, and more particularly to Fig. 1, where a side-view of an 50 internal-combustion motor of approved construction is shown, the parts therein shown as forming part of the internal-combustion motor are all well known and will only be briefly referred to. The casing 10 is provided with cylinders 11 and shaft 12 having flywheel 13 thereon. Suitably connected

with the shaft 12 is a second shaft 15, which as heretofore constructed was a single unbroken shaft, the rotation of which would rotate the members constituting the magneto 16 so as to produce the necessary spark 60 ing for the ignition function.

An embodiment of my invention is applied to the shaft 15, shown in Fig. 1, and consists in providing means for throwing a 65 part of the shaft out of engagement with another part, and then locking the part, when thrown out of engagement, into that position. Or it may also be embodied in a structure where the parts are locked in position 70 during the operation of the motor, and then when it is desired to place these parts into inoperative position the members are unlocked, whereby suitable means bring about the disengagement of the 75 two members necessary for the transmission of the motion from one end of the shaft to the other, an embodiment of which other form is shown in Fig. 6.

Referring again to Fig. 1, the shaft 15 is so divided into two parts, one part of which has secured thereto the recessed member 18 which is secured to the shaft 19 by the key 20, and thereby follows at all times the rotation of the shaft 19. A second member 21 85 is provided with a key-portion 22 which engages a slot 23 arranged in the shaft 15, as clearly shown in Fig. 2, whereby said member 21 is movable longitudinally along the shaft 15, but is prevented from rotating in 90 respect thereto. A yoked member 24 engages the sleeve 21 so as to move it along the shaft 15. This yoked member 24 is supported by and pivoted to the shaft 25, which shaft is suitably supported in the walls of 95 the casing 26. The yoked member 24 has an extension 27 which is engaged by the locking member 29, which is movable by means of a locking mechanism in the casing 30, and which is set into operation by means of a 100 key (not shown) entering at 31 in the usual well-known manner. The casing 26 is provided with suitable shaft-openings and bearings 32 at either side thereof to permit the shafts 15 and 19 to pass therethrough, 105 and the said casing 26 is suitably supported on the casing 10 of the internal-combustion engine.

When it is desired to operate the internal-combustion motor, the locking bolt 29 is 110 withdrawn, and thereby the coiled spring, shown in Fig. 2 and indicated therein by

33, exerts its force against the slidable sleeve 21 and brings this sleeve 21 into engagement with its locking member 18 so as to lock the parts in position, in order that when the shaft 15 is rotated the shaft 19 is rotated with it. When these parts are so locked, the operation is as is well known and the motor may be run as long as desired; but when it is desired to stop the motor and prevent it from being used by persons unauthorized to do so, then the locking bolt 29 is moved outwardly of the lock and the member 27 is depressed, whereby the yoked member 24 is swung around its pivot 25 and the member 21 disengaged from the member 18, and the spring 35 correspondingly compressed, whereby the shaft 15 is free to move independently of the shaft 19 for a short time until the rotational energy there- 20 in expands itself, when the engine comes to a standstill; when the parts are so locked, no unauthorized person can operate the motor, and this becomes especially important in connection with automobiles and motor- 25 boats.

In Fig. 3 another embodiment is shown, wherein the locking parts are arranged upon the shaft that drives the timer 40 of a suitable and approved construction. The 30 parts are substantially the same as those shown in Fig. 2, the shaft 19 being provided with a recessed locking member 18 engageable by the locking member 21 having its circumferential cut-out portion 37 engaged 35 by the yoked member 24, which is pivoted to the shaft 25. The shaft 15 is also provided with the slotted portion 23 to prevent the locking member 21 from rotating, which locking member is provided with a 40 suitable key (not shown in this figure). In this embodiment the extension 27, instead of being acted upon directly by the locking bolt, is connected with a rod 38, which is in turn connected with suitable locking mechanism 45 within handy reach of the operator (not shown in the drawings as the operation thereof is very clear).

In Fig. 4 substantially the same mechanical parts as those shown in Fig. 2, are 50 shown, but they are applied directly in the gear-case to a gear that drives the ignition operating device, be it magneto, timer or other form of ignition. The gear 42, shown in Fig. 4, is provided with the clutch-portion 18 engageable by the clutch-portion 21 movable by the yoked portion 24, which is again pivoted to 25 and has an extension 27. In the embodiment shown in Fig. 4, the extension 27 is provided with a pin 43 which 55 passes therethrough and through the locking bolt 29, which locking bolt is operated by suitable locking mechanism 30.

In the embodiment shown in Fig. 5 sub- 60 substantially the same parts are again shown, but these are connected to the base of the

70 timer, the clutch-portion 18 being immediately connected therewith, which is engageable by the clutch portion 21. In Fig. 5, a suitable collar 44, fixed in position by a thumb-screw 45, is provided.

In the embodiment shown in Fig. 6, the 75 casing 26 with the locking mechanism is arranged close to or as a part of the magneto, but in this case the operation is slightly different from the operation of the parts described in connection with Figs. 1 to 5. Instead of having the spring press the movable clutch member against the fixed clutch member, the spring, now indicated in Fig. 6 by 46, tends to draw the movable clutch member 21 away from the fixed clutch member 18. In order to maintain the two clutch members in locking engagement with each other, the yoke 24 pivoted at 25 is locked in the position shown in Fig. 6 by having the locking bolt 29 of the locking mechanism 30 connected by the pin 43 to the extension 27. When the parts are so locked the clutch members 18 and 21 are brought 80 into locking engagement with each other; but when it is desired to bring these clutch members out of locking engagement with each other, the bolt 29 is moved still further out of the lock 30 and the yoked member 24 thereby is free to move and is moved 85 by the movement of the bolt 29, the spring 46 tending to pull out the clutch member 21 away from the clutch member 18; but it will be seen that in principle the operation of the parts in Fig. 6 is the same as that shown 90 in Figs. 1 to 5, and this principle is applicable to any of the forms of mechanism in Figs. 1 to 5.

95 From the above it will be seen that the basic idea of locking a gasolene or other 100 form of internal-combustion motor in inoperative condition, consists in providing any suitable form of mechanical lock, latch, key, disconnecting link or clutch, or other detachable mechanism on the shaft that drives 105 the timer, magneto or other ignition device. The applications of this idea to commercial 110 forms of mechanism on typical motors may be as shown in the embodiments, which show the application of a locking function to be provided for by any form of lock and key 115 mechanism or any form of easily or quickly operated latch, or other mechanical means for locking or unlocking, which, however, differs from a temporary alteration of this 120 apparatus.

I have shown various embodiments of my 125 invention, but changes may be made therein without departing from the spirit of the invention as defined in the appended claims.

Having thus described my invention, I claim as new and desire to secure by Letters Patent:

1. A locking means for internal-combus- 130 tion motors, having a permanent mecha-

nism, comprising an ignition device, a shaft connecting with the ignition device, and means between the shaft and ignition device for connecting or disconnecting and locking 5 in either operative or inoperative position one part of the permanent mechanism.

2. A locking means for internal-combustion motors, having a permanent mechanism, comprising an ignition device, a shaft 10 connected with the ignition device, means connecting the ignition shaft with the ignition device, disconnectible means arranged in said connecting means, and means for locking in either operative or inoperative 15 position one part of said disconnectible means.

3. A locking device for internal-combustion motors, comprising the ignition driving shaft, an ignition device, means for connecting the ignition device and the driving shaft, clutch members arranged in said means, one of said members being detachable from the other, a forked and pivoted member arranged to operate said disconnectible clutch member, and a locking device for holding the forked and pivoted member in connected or disconnected position.

4. In a locking means for internal-combustion motors, comprising a motor driving

shaft connected to the magneto, timer or other ignition device, an ignition device, connecting means between the ignition driving shaft and ignition device, clutch members arranged therein, one of said members 35 being movable, a pivoted lever member with forked end arranged to operate the movable member, a spring to coöperate with and for acting on said movable member during the locking or unlocking motion, and a locking 40 device for holding the forked and pivoted member in position.

5. A locking device for internal-combustion motors, comprising a rotational element of the motor connecting with the magneto, timer or other ignition device, an ignition device, a permanent mechanism so combined with the rotational element as to provide disconnectible means between that element and the ignition device, and means for locking 45 such disconnectible means in such inoperative position.

In testimony that I claim the foregoing as my invention, I have signed my name in presence of two subscribing witnesses.
